UNITED STATES PATENT OFFICE

BLANCHARD D. SMITH, OF NEW ORLEANS, LOUISIANA

DOG RACING DEVICE

Application filed June 13, 1930. Serial No. 461,028.

My invention relates to improvements in dog racing devices or the like and more particularly to a system for propelling a lure about a dog racing or similar track.

5 Heretofore it has been customary to support the lure on an arm carried by a truck arranged at the side of the track. This arrangement has several disadvantages. The installation is expensive, the projecting arm 10 is unsightly, detracts from the glamor of the race and is a potential danger to the dogs. The noise caused by the truck also detracts from the effectiveness of the race.

15 An important object of my invention is to provide a lure propelling system and apparatus in which these disadvantages are obviated.

Another object of my invention is the provision of a device of this character which is inexpensive and easily installed, and one 20 which is practical and efficient in operation.

Other objects and advantages of my invention will be apparent during the course of the following description.

25 In the accompanying drawings which form a part of this specification, and wherein like characters of reference denote like or corresponding parts throughout the same,

Figure 1 is a plan view of a race track having my invention applied thereto,

30 Figure 2 is a longitudinal section thereof,

Figure 3 is a transverse section through a portion of the track, showing the position of the lure,

Figure 4 is a detail view of the lure,

35 Figure 5 is a transverse sectional view through a portion of the track showing one form of escape for the lure,

Figure 6 is a detail view showing the arrangement of the wires at the escape,

40 Figure 7 is a diagrammatic view of the track showing one arrangement of wires,

Figure 8 is a plan view showing a modified form of escape,

45 Figure 9 is a side elevation thereof.

Figure 10 is a sectional view of a track having a modified form of the lure propelling system,

50 Figure 11 is a front elevation of the wire laying machine, the width of the machine be-

ing exaggerated for convenience of illustration,

Figure 12 is a side elevation thereof,

Figure 13 is a sectional detail view of still another form of my invention, and,

55 Figure 14 is a transverse sectional view thereof.

In the drawings wherein for the purpose of illustration is shown a preferred embodiment of my invention, the numeral 15 designates a race track having an outer fence 16, an inner fence 17, a grandstand 18 and the usual judges stand 19. The inner fence 17 is provided with a series of spaced posts 20 extending upwardly and outwardly over the track. The usual lamps 21 are secured to these posts and light up the track for night racing.

The upper and outer ends of the posts 20 support a trolley or guide rail 22 of any suitable construction and material and this rail extends continuously around the track and at a substantial distance thereabove.

60 The lure is provided with a tube 23 extending through the front portion thereof in a plane slightly inclined rearwardly from the vertical. The tube is provided with flared ends and extends above and below the lure. A spring frame 24 is secured to the tube 23 and supports the usual lure 25.

I purpose to use a suitable wire, cord, thread or similar flexible member 26 to propel the lure about the track. To accomplish this purpose, I bury the wire or other flexible member 26 in the track adjacent the center thereof, and about an inch below the surface of the track. The buried wire circles the track one or more times, and its free end is threaded through the tube 23 in the lure and passed over the rail 22 to the center of the track.

65 At the center of the track I provide a funnel shaped tube 27 having its flared end uppermost and extending to a point substantially higher than the rail 22. The funnel tube 27 is supported on a suitable stand 28. A reel 29 is journaled for rotation within the stand and has its periphery arranged adjacent and in line with the lower open end of the funnel tube 27.

70 In operation, the free end of the wire is passed through the funnel tube and secured

to the reel 29. When the race starts, the reel is rotated at the required speed by any suitable means, such as an electric motor (not shown) and the wire 26 is reeled in. As the wire passes over the rail 22, the pull on the buried portion of the wire when the reel is rotated, is nearly vertical. This reeling in of the wire pulls up the buried wire progressively around the track and causes the wire to slide along the rail which is preferably greased. The lure, by reason of its weight, will slide down the wire and proceed around the track, following the point where the buried wire is being pulled from the ground. Due to the spring frame 24 and the tendency of the lure to be raised with the wire, the lure will travel around the track in a bounding manner simulating the actual running of a live rabbit. The wire will be inclined backwardly as it leaves the ground, as seen in Figures 1 and 4, due to the friction of the wire 26 along the rail 22.

The wire may be laid about the track in a continuous spiral with enough turns to provide for all of the races, or a number of wires may be arranged about the track and their ends joined together. The latter method is preferred as it requires only two circuits of the track in laying the wires.

The wires may be laid in any suitable manner. I have illustrated one means for accomplishing this purpose in Figures 11 and 12. A pair of triangular frames 30 support a wheeled shaft 31 at their apex and have their rear sides extended upwardly to support a handle bar 32. Arranged on the shaft 31 to rotate therewith are a series of peripherally grooved disks 33 which have a radius about one inch greater than the supporting wheels 34. The disks 33 correspond in number to the number of races to be run, and I have illustrated eight. Arranged at the forward apices of the frames 30 is a reel shaft 35 which is removably journaled for rotation in suitable bearings 36. A series of reels 37 are carried by the shaft 35 and each of the reels is aligned with one of the disks 33. Sufficient wire 26 is coiled on each reel to circle the track twice, and the free end of each wire is passed under the adjacent disk, in the peripheral groove therein.

When the reel is moved along the track, the disks 33 will be pressed into the ground by the weight of the machine augmented, if necessary, by a weight 39. The wires will be pressed into the ground and may be covered by a suitable drag or sled 38 which follows the reel. The wires are preferably extended twice about the track to provide ample running of the lure for each race. The ends of adjacent wires may then be connected by means of a sheath or tube 39', see Figures 6, 8 and 9, which is small enough to pass through the tube 23. The finishing end of the first wire is connected to the starting end of the

second wire and so on until all of the wires are connected.

Any suitable form of escape for the lure may be provided. In Figures 5 and 6 I have illustrated one form of escape. Adjacent the finish line of the race is a dummy fence 40 spaced inwardly from the outside fence 16 and tapering rearwardly to the surface of the track. A cover block 41 is arranged above the dummy fence 40 on the inside of the fence 16 and closes the space between the fences 16 and 40 except for a small slot 42 left open above the fence 40 and which widens at the rearward end of the dummy fence to provide an inlet for the lure.

The finish ends of the wires 26 are led through the flared end of the slot 42 and behind the fence 40, and then out into the center of the track. In Figure 6 the relative positions of the wires are shown, their size being exaggerated for convenience of illustration. In order to use the dummy fence escape it is necessary to interlace the wires. Starting with four races to be run, the wire *a* leaves the escape, circles twice about the track and then crosses over the wires *b*, *c* and *d* and enters the escape where it is connected to the starting end of wire *b*. The wires that cross the track to enter the escape must pass under the wires which are first pulled up and over the other wires. Wire *a* when crossing the track must pass over wires *b*, *c* and *d* and under wire *a*. Wire *b* must pass over wires *c* and *d* and under wires *a* and *b*. Wire *c* must pass over wire *d* and under wires *a*, *b* and *c*.

Figure 7 shows diagrammatically the course which the wires take in twice circling the track.

In Figures 8 and 9 I have shown another form of escape for the lure. An escape box 43 is provided with an open rear end and an open lower side. An opening 44 is arranged in the top of box 43 adjacent the forward end thereof and is connected to the rear of the box by a slot 45 which increases in width as it approaches the rear of the box and is flared outwardly at its rearward end. A pair of flaps 46 of flexible material are joined to the sides of the box and converge inwardly. The escape box is placed over the finish end of the wire 26 and the lure will enter through the flaps 46, the wire being guided into the opening 44 by the flared slot 45. The box will be carried along the track by the wire 26 until the reel 28 is stopped, and the lure will be concealed by the flaps 46. The box 43 may then be removed for the start of the next race.

When the escape box 43 is used it is not necessary to interlace the wires but they may be arranged in a continuous spiral.

In Figure 10 I have provided a modification of my invention in which the wires are not buried in the track. An annular gutter

is formed around the track by means of a continuous strip 47 secured to the inner fence 17 adjacent the bottom thereof, and the wires are coiled about the inner fence below the strip 47. When the wire is reeled in, the lure will be kept out on the track in the position shown in Figure 10 by centrifugal force acting in the direction of the arrow.

Another alternative is shown in Figures 13 and 14. A tube 48 is buried in the track and is provided with a narrow slot 49 on its upper side. The wire 26 is arranged in the tube and is pulled through the slot 49 which is so narrow that the dogs' feet cannot be caught therein.

Very fine wire may be used, or if desired, waxed shoemaker's thread may be substituted for the wire. At night time the wire or thread will be invisible and the lure will seem to be moving under its own volition.

The rail 22 is arranged at such a height that the incoming wire will clear the judges stand 19.

The wires may be laid in the afternoon before the races and the small furrow left by the pulled in wire will not affect the racing animals. The track need not be leveled before laying the wires.

If desired the lure may be raised from the track at the end of the race, as by means of a crosspiece, disk or enlargement secured to the wire as at 50 in Figure 10, and of such size as to be incapable of passing through the tube 28.

It will be seen that I have provided a lure propelling system which is simple, effective and inexpensive to install and to operate and which avoids the disadvantages of the usual lure propelling devices.

While I have shown and described the preferred embodiment of my invention, it is to be understood that various changes in the size, shape and arrangement of parts may be resorted to without departing from the spirit of my invention or the scope of the subjoined claims.

Having thus described my invention, what I claim and desire to protect by Letters Patent is:

1. The combination with a race track, of a flexible member encircling said track, a lure slidably engaging said flexible member, and means to propel said lure along said flexible member.

2. The combination with a race track, of a flexible member encircling said track, a lure engaging said flexible member, and means to move said flexible member relatively to the lure.

3. The combination with a race track, of a flexible member encircling said track, a lure slidably engaging said flexible member, and means to exert an upward pull on said flexible member to move said flexible member relatively to the lure.

4. The combination with a race track, of a flexible member encircling said track, a lure slidably engaging said flexible member, and means to reel in said flexible member.

5. The combination with a race track, of a lure having a guide member, a flexible member encircling said track and having one end extending freely through the guide member of the lure, whereby the lure is capable of sliding movement relative to the flexible member, and means to reel in said flexible member.

6. The combination with a race track, of a lure having a guide member, a flexible member encircling said track and having one end extending upwardly through the guide member of the lure, and means to pull said flexible member through the guide member of the lure.

7. The combination with a race track, of a lure having a guide member, a rail encircling said track and arranged thereabove, a flexible member encircling said track and having one end extending upwardly through the guide member of the lure and over the rail, and means to pull said flexible member through the guide member of the lure and over the rail.

8. The combination with a race track, of a reel, a tube extending upwardly from said reel, a rail arranged about said track and a substantial distance thereabove, a lure having a guide member, a flexible member arranged about said track and having one end extended upwardly through the guide member of the lure, over the rail to the tube and through the tube to the reel, and means to operate the reel to pull the flexible member through the guide member of the lure and over the rail, whereby the lure will be propelled about said track.

9. The combination with a race track, of a rail arranged about said track and a substantial distance thereabove, a reel, a lure having an opening extending upwardly therethrough, a runner arranged below said lure, a flexible member arranged about said track and having one of its ends extended through the opening in the lure, and over the rail to the reel, whereby when the reel is operated to pull in the flexible member, the lure will be propelled about the track.

10. The combination with a race track, of a lure having an opening therein, a flexible member arranged beneath the surface of said track and encircling the same, one end of said flexible member being extended upwardly through the opening in the lure, and means to pull said flexible member from the track and through the lure.

11. The combination with a race track, of a rail arranged thereabout and a substantial distance thereabove, a lure having an opening extending upwardly therethrough, a flexible member arranged beneath the surface of

said track and encircling said track, one end of said flexible member being passed through the opening in the lure and over the rail, and means to pull the flexible member from the track and through the lure.

12. The combination with a race track, of a rail arranged thereabout and a substantial distance thereabove, a lure having an opening extending upwardly therethrough, a flexible member embedded in the soil of said track and encircling the track, one end of said flexible member extending through the opening in the lure and over the rail, a reel adapted to engage the flexible member and pull it from the soil of the track.

13. The combination with a race track, of a rail arranged thereabove, a lure having an opening extending upwardly therethrough, a relatively thin flexible member embedded in the soil of said track and encircling the track, one end of said flexible member extending through the opening in the lure and over the rail, a reel, and a tube extending upwardly above said reel, the flexible member passing downwardly through the tube to the reel, whereby the reel will operate to pull the flexible member from the soil of the track and propel the lure about the track.

14. The combination with a race track, of a lure having an opening therethrough, a flexible member arranged below the surface of the track and having one end passed upwardly through the opening in the lure, means to pull the flexible member through the lure and away from the track to propel the lure about the track, and an escape for said lure arranged above a portion of said flexible member.

15. The combination with a race track, of a lure having an opening therein, a resilient runner arranged below said lure, a flexible member arranged about said track and having one end threaded through the opening in the lure, and means to pull the flexible member through the lure to propel the lure about the track.

16. The combination with a race track, of a lure having an opening extending upwardly therethrough, a resilient runner arranged beneath the lure, a flexible member arranged about said track and embedded therein, said flexible member having one end threaded through the opening in the lure, and means to pull the flexible member through the lure and out of the track to propel the lure about said track.

17. A device for propelling an object over the ground, the object having an opening extending upwardly therethrough, comprising a flexible member embedded in the ground, the end of the flexible member passing through the opening in the object to be propelled, and means for pulling the flexible member upwardly through the object to be propelled and away from the ground.

18. The combination with a race track, of a lure having an opening therethrough, a tube embedded in the track and extending thereabout, and having a slot in the upper side, a flexible member arranged in said tube and having one end passed through the slot therein and upwardly through the opening in the lure, and means to pull the flexible member through the lure.

19. The combination with a race track, of a gutter arranged about said track adjacent the inner edge thereof, a flexible member arranged about the track and in said gutter, a rail arranged above said track, a lure having an opening therethrough, the flexible member being passed through the lure and over the rail, and means to pull the flexible member over the rail to propel the lure about the track in a path spaced from the inner edge of the track.

In testimony whereof I affix my signature.
BLANCHARD D. SMITH.
